UNITED STATES PATENT OFFICE.

CHARLES LESTER MAINLAND, OF HOLLIS, LONG ISLAND, NEW YORK.

VALVE-LIFTER GUIDE.

1,409,878.

Specification of Letters Patent. Patented Mar. 14, 1922.

Application filed September 14, 1920. Serial No. 410,281.

To all whom it may concern:

Be it known that I, CHARLES L. MAINLAND, a citizen of the United States, and a resident of Hollis, Long Island, in the 5 borough of Queens, county of Queens, and State of New York, have invented a new and Improved Valve-Lifter Guide, of which the following is a full, clear, and exact description.

10 This invention relates to an improvement in guides or bearings, and has particular relation to a lifter guide, especially designed for use in connection with the tappet valves of an internal combustion engine.

15 The invention broadly contemplates a guide for reciprocating members, provided with means which improves the working and increases the life of both the member and the guide.

20 Another object of the invention is to provide an adjustable means for a guide which automatically compensates for wear on both the reciprocating member and the guide.

25 A more specific object of the invention is to provide in combination with the lifter guide of a valve, means which silences and prevents rattling, due to vibration resulting from wear.

30 A further object in view resides in the provision of a silencing and wear compensating means of this character which is removable whereby to admit of replacement or repair of the means when worn.

35 A still further object of the invention is to provide a device of the character described which is extremely simple in construction, inexpensive to manufacture and highly efficient in its purpose.

40 With the above recited and other objects in view, some of which will be more apparent from the following detailed description, reference is had to the accompanying drawings forming a part of this application, and in which:

45 Figure 1 is a diagrammatic fragmentary sectional view of a tappet valve, push rod, lifter guide and cam, said lifter guide being constructed in accordance with the invention and partly broken away to disclose the 50 underlying structure.

Figure 2 is a horizontal sectional view taken on the line 2—2 of Figure 1.

Figure 3 is a vertical sectional view taken on the line 3—3 of Figure 1.

55 Referring to the drawings by characters of

reference, 10 designates a tappet valve having the usual valve stem 11, the lower extremity of which is received by the push rod 12 which is bifurcated at its lower extremity as at 13 to provide a bearing for the 60 roller 14. A cam shaft 15 of usual construction provided with a cam 16 serves to intermittently lift the valve.

In the usual form of lifter guides, it has been found that the push rod and the guide 65 due to constant operation become worn after continued use, to such an extent that lost motion results in rattling. In order to compensate for this wear and silence the operation of the tappet valve, means is provided 70 for automatically taking up the wear. In the improved form of lifter guide 17, the same is recessed as at 18, and a removable section 19, is arranged in said recess. The removable section and the lifter guide are provided 75 with registering exterior grooves 20—20 and a split resilient ring 21 is arranged in said grooves and embraces both the removable section and the guide at this point. If desired, the extremities of the ring may be 80 turned in as at 22 to bite into and grip either the guide or the removable section. In positioning the guide on the push rod, it is desirable to arrange the recess and removable section on the side on which the 85 cam 16 strikes the roller, as it has been found that the wear usually occurs on this side. By this arrangement it will be seen that the resilient ring will exert a tension to normally effect the contraction of the guide 90 and section 18 on the push rod for the purpose of automatically taking up wear. When the push rod, guide and its removable section have become worn to such an extent that the confronting faces of the removable 95 section and the guide abut, the removable section may be taken off and its confronting face ground to admit of its further use.

From the foregoing it will be seen that a simple and effective means for overcoming 100 the disadvantages of the present type of guide is provided, but it is understood that no limitation is necessarily made to the precise structural details, as the right to embodiments other than those actually illustrated herein is reserved to the full extent indicated by the general meaning of the terms in which the claims are expressed and by variations in the phrasing of the same.

Having thus described my invention, I 110

claim as new and desire to secure by Letters Patent:

1. A lifter guide for push rods comprising a tubular guide member, having an axial recess, a semi-tubular section arranged in said recess, and a resilient split ring embracing the guide member and said removable section for normally effecting relative axial movement of said guide member and removable section.
2. A valve lifter guide, comprising a tubular member having an axial recess therein, a section arranged in said recess, and resilient means embracing and coacting respectively with the tubular member and

said section for normally pressing said section against the valve lifter whereby to compensate for wear on the valve lifter, the section, and said guide.

3. The combination with a valve lifter rod, of a guide therefor, comprising a tubular member having an axial recess, a movable section mounted in said recess, and resilient means for removably retaining said section in said recess and effecting movement of the same to exert a pressure on the lifter rod whereby to compensate for wear on said elements.

CHARLES LESTER MAINLAND.
